Primary Examiner — Ricky Pham(74) *Attorney, Agent, or Firm* — Adler Pollock & Sheehan P.C.(57) **CLAIM**

The ornamental design for a fry basket, as shown and described.

DESCRIPTION

FIG. 1 is a perspective view of a fry basket in accordance with the subject disclosure.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken line showings are included for the purpose of illustrating portions of the invention and form no part of the claimed design.
